Assistant Examiner — Catherine Ho

(74) *Attorney, Agent, or Firm* — Ladas & Parry, LLP(57) **CLAIM**

The ornamental design for a digital information display device, as shown and described.

DESCRIPTION

FIG. 1 is a perspective view of a digital information display device, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view of a digital information device shown with an environmental support element.

The broken lines in the figures show portions which form no part of the claimed design.

The dot-dot-dash broken line shows environment with forms no part of the claimed design.

1 Claim, 5 Drawing Sheets
